CLAIM

The ornamental design for a bone plate, as shown and described.

DESCRIPTION

FIG. 1 is a top perspective view of a bone plate in accordance with a first embodiment of our new design;
FIG. 2 is a bottom perspective view thereof;

FIG. 3 is a top plan view thereof;

FIG. 4 is a right side elevation view thereof;

FIG. 5 is a left side elevation view thereof;

FIG. 6 is a front elevation view thereof;

FIG. 7 is a rear elevation view thereof;

FIG. 8 is a bottom plan view thereof;

FIG. 9 is a top perspective view of a bone plate in accordance with a second embodiment of our new design;

FIG. 10 is a bottom perspective view thereof;

FIG. 11 is a top plan view thereof;

FIG. 12 is a right side elevation view thereof;

FIG. 13 is a left side elevation view thereof;

FIG. 14 is a front elevation view thereof;

FIG. 15 is a rear elevation view thereof;

FIG. 16 is a bottom plan view thereof;

FIG. 17 is a top perspective view of a bone plate in accordance with a third embodiment of our new design;

FIG. 18 is a bottom perspective view thereof;

FIG. 19 is a top plan view thereof;

FIG. 20 is a right side elevation view thereof;

FIG. 21 is a left side elevation view thereof;

FIG. 22 is a front elevation view thereof;

FIG. 23 is a rear elevation view thereof;

FIG. 24 is a bottom plan view thereof;

FIG. 25 is a top perspective view of a bone plate in accordance with a fourth embodiment of our new design;

FIG. 26 is a bottom perspective view thereof;

FIG. 27 is a top plan view thereof;

FIG. 28 is a right side elevation view thereof;

FIG. 29 is a left side elevation view thereof;

FIG. 30 is a front elevation view thereof;

FIG. 31 is a rear elevation view thereof;

FIG. 32 is a bottom plan view thereof;

FIG. 33 is a top perspective view of a bone plate in accordance with a fifth embodiment of our new design;

FIG. 34 is a bottom perspective view thereof;

FIG. 35 is a top plan view thereof;

FIG. 36 is a right side elevation view thereof;

FIG. 37 is a left side elevation view thereof;

FIG. 38 is a front elevation view thereof;

FIG. 39 is a rear elevation view thereof;

FIG. 40 is a bottom plan view thereof;

(Continued)

FIG. 41 is a top perspective view of a bone plate in accordance with a sixth embodiment of our new design; FIG. 42 is a bottom perspective view thereof; FIG. 43 is a top plan view thereof; FIG. 44 is a right side elevation view thereof; FIG. 45 is a left side elevation view thereof; FIG. 46 is a front elevation view thereof; FIG. 47 is a rear elevation view thereof; FIG. 48 is a bottom plan view thereof; FIG. 49 is a top perspective view of a bone plate in accordance with a seventh embodiment of our new design; FIG. 50 is a bottom perspective view thereof; FIG. 51 is a top plan view thereof; FIG. 52 is a right side elevation view thereof; FIG. 53 is a left side elevation view thereof; FIG. 54 is a front elevation view thereof; FIG. 55 is a rear elevation view thereof; FIG. 56 is a bottom plan view thereof; FIG. 57 is a top perspective view of a bone plate in accordance with an eighth embodiment of our new design; FIG. 58 is a bottom perspective view thereof; FIG. 59 is a top plan view thereof; FIG. 60 is a right side elevation view thereof; FIG. 61 is a left side elevation view thereof; FIG. 62 is a front elevation view thereof; FIG. 63 is a rear elevation view thereof; and, FIG. 64 is a bottom plan view thereof.

The broken lines depict portions of the bone plates that form no part of the claimed design. It is contemplated that other embodiments of the design may include any part, portion, element, or any combination thereof shown in the figures. It is specifically contemplated

that any and all solid lines and portions thereof may be converted to broken lines, whether in subsequent division or continuation applications and/or amendment.
